UNITED STATES PATENT OFFICE.

RUFUS J. LIPE, OF DELTA, COLORADO.

DESIGN FOR A WEEDEER.

SPECIFICATION forming part of Design No. 25,667, dated June 23, 1896.

Application filed May 16, 1896. Serial No. 591,882. Term of patent 7 years.

To all whom it may concern:

Be it known that I, RUFUS J. LIPE, of Delta, in the county of Delta and State of Colorado, have invented and produced a new and original Design for a Weeder, of which the following is a full, clear, and exact description.

Reference is to be had to the accompanying drawings, forming a part of this specification, in which similar characters of reference indicate corresponding parts in both the views.

Figure 1 is a side elevation of a weeder embodying my new design, and Fig. 2 is a plan view thereof.

The design in its entirety comprises the blade, bow, and tang, the blade being of zigzag form and the ends of the blade *a* ranging forwardly and outwardly and having upward side extensions *b*, the back and front edges of which extensions are convergent, 20 the bow *c* being of curved form, as seen in

plan, and disposed at an angle to and ranging rearwardly from the blade, and the lines of the tang *d* departing rearwardly from the center of the bow.

The leading feature of the design consists 25 of the zigzag blade, the ends of which range forwardly and terminate in upward side extensions, the bow departing rearwardly from and disposed at an inclination to the said upward extensions of the blade, and the tang, 30 the lines of which depart rearwardly from the center of the bow.

I claim—

The design for a weeder herein shown and described.

RUFUS J. LIPE.
